UNITED STATES PATENT OFFICE.

FRANK T. COPE, OF SALEM, OHIO, ASSIGNOR TO THE ELECTRIC FURNACE COMPANY, OF SALEM, OHIO, A CORPORATION OF OHIO (INCORPORATED 1923).

HEAT-TREATING FURNACE.

Application filed November 20, 1924. Serial No. 751,024.

To all whom it may concern:

Be it known that I, FRANK T. COPE, a citizen of the United States, residing at Salem, in the county of Columbiana and 5 State of Ohio, have invented certain new and useful Improvements in Heat-Treating Furnaces, of which the following is a specification.

This invention relates to furnaces especially adapted for heat treating small articles such as automobile gears and the like, and the objects of the improvement are to provide a continuous furnace in which the articles to be treated are suspended in the 10 heating chamber from blocks slidably carried in a slot in the roof of the furnace and overlapping to keep the slot sealed at all times, means being provided for intermittently or continuously moving the blocks 15 forward through the furnace, the parts being so arranged that as each article is properly heat treated, it is carried out of the discharge end of the furnace.

The above and other objects may be attained by constructing the furnace in the manner illustrated in the accompanying drawings, in which—

Figure 1 is a vertical, longitudinal section through a furnace embodying the invention;

Fig. 2, a transverse sectional view of the furnace;

Fig. 3, an end view of the same; and

Fig. 4, a detached isometric detail of one 35 of the movable blocks from which the articles are supported.

Similar numerals refer to similar parts throughout the drawings.

The furnace is indicated generally at 1, and may be of any length necessary to produce the desired heat treatment. The heating chamber 2 of the furnace may be heated electrically or by any other well known means, and need only be of sufficient cross sectional area to accommodate the articles 40 to be passed therethrough.

An entrance or charging opening 3 is provided at one end of the heating chamber, and a similar discharge opening 4 at the opposite end. Although doors may be provided for these openings and arranged to be automatically opened and closed to permit the entrance and exit of the articles under treatment, it is not thought necessary to illustrate the same, and for the purpose of this

invention, it may be assumed that the doors are dispensed with.

The roof 5 of the furnace is provided with a central, longitudinal slot 6, which may be reinforced as by the angle irons 7. The articles to be heat treated, which in the present case are shown as automobile gears, indicated at 8, are suspended upon hooks 9 carried by the blocks 10, provided with the overlapping shoulders 11 at their ends, and 65 having the depending ribs 12 arranged to slidably fit within the slot 6, a lug 13 being formed upon the upper side of each block.

These blocks are located continuously along the slot 6 throughout the entire length 70 of the furnace, and thus effectually seal the slot and prevent loss of heat through the same. The track members 7 are preferably extended for a distance beyond each end of the furnace, for the purpose of charging and 75 discharging.

In order to intermittently move the blocks forward along the slot 6, a reciprocating push rod 14 is provided and arranged to be continuously reciprocated in any well 80 known manner.

One or more pawls 15 are pivotally mounted upon the rod 14 and inclined forward and downward to engage the lugs 13 of the sliding blocks, whereby with each reciprocation of the rod, the pawl 15 will ride backward over one or more blocks and then engage with one of the lugs 13 to carry the blocks forward with the next forward movement of the push rod. 85

If desired, the track 7 may be continuous, extending over the discharge end of the furnace back to the charging end, whereby the blocks always remain thereon. Thus it is only necessary for an operator to place the 90 gears or other articles upon the hooks 9 as they near the charging end of the furnace, while a second operator may remove the treated articles from the hooks as they emerge from the discharge end of the furnace, the blocks with the empty hooks continuing to travel back to the charging position. 100

It will be evident that instead of the intermittent movement given to the blocks by the reciprocating push rod, any well known mechanism may be provided for continuously moving the blocks forward along the roof of the furnace. 10

Although a straight furnace is illus- 11

trated, it should be understood that the invention is applicable to a rotary furnace, by providing a circular slot in the roof thereof, and although the hooks are shown as depending from independent blocks, it is pointed out that they may depend from a plate slidably mounted over the slot and sealing the same in any well known manner.

I claim:—

- 10 1. A furnace provided with a slot in its roof, abutting blocks provided with article supporting rods depending through said slot, and means for moving the blocks along the slot.
- 15 2. A furnace provided with a slot in its roof, overlapping blocks provided with article supporting rods depending through said slot, and means for moving the blocks along the slot.
- 20 3. A furnace having a longitudinal slot in its roof, blocks provided with ribs slidably mounted in the slot, article supporting rods depending from the blocks, and means for moving the blocks forward along the slot.
- 25 4. A furnace having a longitudinal slot in its roof, overlapping blocks provided with ribs slidably mounted in the slot, article supporting rods depending from the blocks, and means for moving the blocks forward along the slot.
- 30 5. A furnace having a longitudinal slot in its roof, overlapping blocks provided with ribs slidably mounted in the slot, article supporting rods depending from the blocks, and means for moving the blocks forward along the slot.

5. A furnace having a longitudinal slot in its roof, blocks provided with article supporting rods depending through said slot, lugs upon the upper sides of the blocks, and means for engaging said lugs to move the blocks forward along the slot.

6. A furnace having a longitudinal slot in its roof, overlapping blocks provided with article supporting rods depending through said slot, lugs upon the upper sides of the blocks, and means for engaging said lugs to move the blocks forward along the slot.

7. A furnace having a longitudinal slot in its roof, blocks provided with article supporting rods depending through said slot, lugs upon the upper sides of the blocks, a reciprocating push rod having a pawl for engagement with said lugs, and means for engaging said lugs to move the blocks forward along the slot.

8. A furnace provided with a slot in its roof, article supporting rods depending through said slot, and means for moving the rods forward through the slot and means for keeping the slot closed as the rods are moved therethrough.

In testimony that I claim the above, I have hereunto subscribed my name.

FRANK T. COPE.
